UNITED STATES PATENT OFFICE.

GEORGE E. BEDELL, OF HERKIMER, NEW YORK.

FOLDING COT.

SPECIFICATION forming part of Letters Patent No. 274,455, dated March 27, 1883.

Application filed January 6, 1883. (No model.)

To all whom it may concern:

Be it known that I, GEORGE E. BEDELL, a citizen of the United States, residing at the village of Herkimer, Herkimer county, and 5 State of New York, having invented and discovered a new and useful Folding Cot, of which the following is a specification.

My invention relates to improvements in the method of folding an ordinary cot into a compact space by means of a longitudinal slot in one end of the side rail, so as to allow the side rails to oscillate when the legs of the cot are opened and shut. I attain this object by the means demonstrated in the accompanying 10 drawings, in which—

Figure 1 shows part of cot and legs, with the slot in the side rail. Fig. 2 shows end view of the cot open. Fig. 3 shows side view of the cot with legs open, and dotted lines show cot with 15 legs half-shut. Fig. 4 shows cot folded into a compact space.

Similar letters refer to similar parts throughout the several views.

The nature and construction of my invention 20 consists of an ordinary folding cot with two pairs of legs, X-shaped, three of which legs are loosely bolted or riveted to longitudinal bars or side rails, while the fourth leg is secured to the side rail by means of a bolt or rivet passing 25 through the end of the leg into and through a longitudinal slot in the side rail. The length of the slot will be the thickness of the two legs of the cot, and of sufficient width to allow 30 the bolt or rivet to work loosely. The legs of 35 the cot, thus fastened or secured to the side bars, can be easily opened or closed by the oscillation of the side rails by allowing the bolt or rivet to work in the slot by means of the fulcrum produced by the bolting or riveting 40 of the three legs to the side bars of the cot at unequal distances, so that the cot can be opened and closed into a compact space.

Having described the nature and construction of my invention and improvement, I will 45 now describe its construction and operation by reference to the drawings.

A represent the side bars of the cot. B B' in Fig. 1 show the legs of the cot closed; B B', the legs and fastening, when working in the 50 slot C, bolted or riveted to the side bar; C, the

longitudinal slot in one end of the side rail, through which one of the legs of the cot is loosely bolted or riveted; D, the brace and pin to hold the legs in place when the cot is spread for use; E, pin to hold legs B B' in position 55 when the cot is opened for use. The oscillating motion of the side bar by means of the slot and rivet, or both, working in the same when the legs of the cot are opened or folded, is shown in Figs. 1, 3, and 4 of drawings. 60

I am aware of folding cots with X-shaped legs attached to the side bars by means of bolts or rivets, with angle-irons or hinges and other similar devices, by means of which the ends of the legs are deflected toward each other, so as to bring the pivoting-point of the legs to the side rail in the same axis, and that various devices have been resorted to to overcome the difficulty of bolting or riveting the legs to the side rails at unequal distances, thereby 65 preventing folding the legs inside of the side rails. I do not therefore make a broad claim to a folding cot; but

What I do claim as my invention and discovery, and that which I desire to secure by 70 Letters Patent, is—

1. The combination, in a portable folding cot, having two pairs of legs X-shaped, three of which legs are loosely attached to the side bars by bolts or rivets, and the fourth leg loosely 75 attached to the side bar by bolt or rivet passing through the top end of the leg through a longitudinal slot in the side rail corresponding in length to the width of the two legs, the legs being so attached to the slotted end of the side 80 rail as to allow the bolt or rivet to move in the slot when the legs of the cot are opened or closed, as described.

2. A movable side rail to a folding cot with X-shaped legs, and longitudinal slot S and 85 bolt or rivet C, so attached that the rail will oscillate by means of the slot S, rivet C, and fulcrum, so that the side bars will oscillate to allow the legs of the cot to be opened and closed or folded into a compact space, as and 90 for the purposes specified.

GEO. E. BEDELL.
